UNITED STATES PATENT OFFICE.

EMIL C. STEFFEN, OF LOS ANGELES, CALIFORNIA.

DESIGN FOR A GAME APPARATUS.

58,259.

Specification for Design. Patented June 28, 1921.

Application filed January 31, 1921. Serial No. 441,494. Term of patent 7 years.

To all whom it may concern:

Be it known that I, EMIL C. STEFFEN, a citizen of the United States, residing at Los Angeles, in the county of Los Angeles and State of California, have invented a new, original, and ornamental Design for a Game Apparatus, of which the following is a specification, reference being had to the accompanying drawing, forming part thereof.

The figure is a front view of the game apparatus showing my new design.

I claim:

The ornamental design for a game apparatus as shown.

EMIL C. STEFFEN.
